UNITED STATES PATENT OFFICE.

FREDERICK A. INGALLS, OF BREMEN, ILLINOIS, ASSIGNOR TO WYMAN-GORDON COMPANY, OF WORCESTER, MASSACHUSETTS, A CORPORATION OF MASSACHUSETTS.

EARTH-BORING APPARATUS AND METHOD OF MAKING SAME.

Application filed August 22, 1921. Serial No. 494,643.

To all whom it may concern:

Be it known that I, FREDERICK A. INGALLS, a citizen of the United States, and a resident of the township of Bremen, in the county of Cook and State of Illinois, have invented certain new and useful Improvements in Earth-Boring Apparatus and Methods of Making Same, of which the following is a specification.

10 This invention relates to earth boring apparatus and the method of making the same but more particularly to jars for use in drilling deep wells, and has for its primary object to economically produce a superior article of this class.

Further objects of the invention are to eliminate all welding in the production of the jar and thus make possible the use of a higher grade of steel; to provide uniformity in the physical characteristics of the steel throughout, and to provide a jar construction which may be produced practically entirely by forging.

The well-known link type of jar is generally composed of two members or links, one of which is formed solid or without joints, whereas the other link is initially open or formed of more than one piece to permit assembly or interlinking with the closed link. This open link is closed subsequent to assembly and the joints are quite generally welded. It has been found in practice that these welded joints form a source of weakness in the jar. I have devised a form of jar construction in which the open or jointed link may be quickly and easily closed and when closed possesses the strength and durability of a solid or non-jointed link.

40 The many other objects and advantages of my invention will be better understood by reference to the following specification when considered in connection with the accompanying drawings illustrating certain selected embodiments thereof, in which:—

Fig. 1 is an elevation of the upper jar member at the completion of the initial forming operation.

Fig. 2 is the same as Fig. 1 but with one 50 of the reins bent slightly outwardly to permit the interlinking of this member with the lower jar member.

Fig. 3 is the same as Fig. 1, bottom plan view.

Fig. 4 is an elevation of the lower jar member.

Fig. 5 is an elevation of the jar illustrating the method of interlinking the upper and lower members.

Fig. 6 is an elevation partially in section of the completed and assembled jar.

Fig. 7 is an elevation of a modified form of upper jar member.

Figs. 8 and 9 are respectively sections on the lines 8—8 and 9—9 of Fig. 6.

Referring to the drawings, the jar comprises two members 10 and 11 which will hereinafter be referred to as the upper and the lower jar members respectively but it will be readily appreciated that the relative positions of these members may be reversed. The form of these members when completed and assembled is substantially the same with the exception that the upper member is provided with a threaded tang 12 for attachment to the lower end of the operating member and the lower member contains a threaded socket 13 to receive the boring tool, as is customary in this type of jar.

The upper member 10 of the jar consists of a head 17 provided with reins 14 and 15 having their outer ends connected by a web 16. The rein 15 forms an extension of the head. The rein 14 is bent outwardly from the rein 15 sufficiently to permit the assembling or interlinking of the members 10 and 11 in the manner illustrated in Fig. 5. Subsequent to the assembling operation, this rein 14 is bent inwardly into parallel relation with the rein 15 and the inner end portion of this rein rests upon the seat 19 in the head. The end 18 of the rein fits tightly against the shoulder 22 on the head. The seat 19 in the head is preferably raised above the inner face of the rein 15 the width of the slot 21 so that the shoulder 20 shall form an undivided end wall for the slot.

Any suitable means may be provided for rigidly retaining the inner end of the rein 14 upon the seat 19 but I have found a very advantageous construction to be that shown in Figs. 1 to 6 inclusive in which an inwardly projecting lug 23 is formed on the rein to enter a perforation 24 in the head when the rein is bent inwardly to close the links. The outer end of this lug is turned over to form a head fitting tightly within the conical enlargement 25 of the perfora-

tion. This lug absolutely rigidly binds the rein to the head. The lug and perforation are preferably elliptical in cross section as indicated in Fig. 3.

5 In the form of my invention shown in Fig. 7 of the drawings, the construction is practically the same as in the previously described embodiment with the exception that the binding lug has been omitted and oppositely disposed perforations 26 and 27 have been drilled through the rein 28 and the head 29. The inner end of the rein 28 is secured to the head 29 by a bolt or rivet (not shown) passed through these perforations 15 after the rein has been bent into parallel relation with the opposite rein.

The jointed member 10 of the jar is initially formed between forging dies preferably in the shape indicated in Fig. 1 and the 20 flash removed by a trimmer. The perforation 24 is then formed by drilling. The member is next preferably heated at 30 to facilitate the bending of the rein 14 and this rein is then bent outwardly sufficiently 25 to permit the interlinking or assembling of the members of the jar. It will be readily evident that the rein 14 may be initially formed in this outer position but in practice it has been found more satisfactory to 30 forge the rein in an intermediate position.

The member 11 is initially forged as shown in Fig. 4 and then the reins 31 and 32 are warped apart into the form indicated by dotted lines to permit the interlinking of 35 the members. The members are then inter-linked in the manner indicated in Fig. 5 and brought to the relative position shown in Fig. 6. The jar is next placed in an upsetting machine and the rein 14 brought into 40 parallel relation with the rein 15, forcing the lug 23 through the perforation 24 and turning over the end of the lug to form the head 33 fitting within the conical recess 25. The jar is then struck between forging dies 45 to return the reins of the member 11 to their normal or parallel relation. The threading of the tang 12 and the socket may be performed either before or after the assembling of the jar members but this operation forms 50 no part of the forging operation constituting the present invention.

The method of making the form of jar link shown in Fig. 7 is substantially the same as that described for the previous embodiment with the exception that perforations are drilled through both the head and the free rein. Upon the completion of the 55 assembling operation, the rein 28 is bent into parallel relation with the fixed rein 34 and held tightly in this position while a bolt or rivet is inserted through the registering perforations 26 and 27. This bolt or rivet performs the same function as the lug 23 in the previous embodiment.

65 This form of jar is as strong and durable

as though both links were initially forged without joints and no welding is necessary. Very little strain comes on the joint during the drilling operation of the jar as the upper end of the lower jar member strikes 70 against the shoulder 20 on the head. The lug securing the free end of the rein to the head is of greater strength than either of the reins so that a rupture of the reins will take place before the joint will break. As 75 no welding is necessary, a high-grade of steel may be used. The absence of welded joints provides a uniformity in the physical characteristics of the metal throughout which is lacking in a jar having such joints so for it is well recognized that welding weakens the steel about the joints.

The jar is practically completely produced by forging and the process is a simple and economical one. When once assembled and 85 completed the members or links composing the jar are permanently maintained in perfect alignment and will not jam.

I am aware that many changes may be made in the form of the parts and the 90 method of their production and assembly without departing from the spirit of my invention and I reserve the right to make all such as fairly fall within the scope of the following claims. 95

I claim as my invention:

1. A jar link comprising a head having a rein forming an extension thereof, a second rein connected at its outer end to the outer end of the first mentioned rein, and means 100 for attaching the inner end of the second rein to said head.

2. A jar link comprising a one-piece head having a rein forming an extension thereof, a second rein connected at its outer end to the outer end of the first rein, and means for 105 attaching the inner end of the second rein to said head.

3. A jar link comprising a head having a rein forming an extension thereof, a second 110 rein connected at its outer end to the outer end of the first rein and having its inner end free, and means for providing an interlocking engagement between said free end and said head. 115

4. A jar link comprising substantially parallel reins having their outer ends connected and their inner ends separated, and means for providing an interlocking engagement between the inner ends of said 120 reins.

5. A jar link comprising a pair of substantially parallel reins having their outer ends connected and their inner ends separated, and means on one of said reins for engaging the other rein to provide a connection between said separated ends. 125

6. A jar link comprising a pair of substantially parallel reins having their outer ends connected and their inner ends sepa- 130

rated, and a lug formed on one of said reins adapted to enter a corresponding socket in the other rein to form a connection between the inner ends of said reins.

5 7. A jar link comprising a head having a rein forming an extension thereof, a second rein connected at its outer end to the outer end of the first mentioned rein and having its inner end free, and a lug on the free end 10 of the second rein adapted to enter a socket in said head and be retained therein to form a connection between said free end and said head.

8. A jar link comprising a head having a 15 rein integral therewith and forming an extension thereof, a second rein connected at its outer end to the outer end of the first mentioned rein and having its inner end free, and a lug on the free end of the second rein 20 adapted to be pressed through a perforation in said head and the outer end of the lug headed to form a permanent connection between said free end and said head.

9. The method of making a jar link which

consists in initially forming the link between 25 forging dies with the reins connected at one end and separate at the other end, and securing together the separated ends of the link.

10. The method of making a jar link 30 which consists in forging the reins with their outer ends connected and a head formed on the free inner end of one of the reins, and attaching the free inner end of the other rein to said head.

35 11. The method of making a jar link which consists in forming the reins with their outer ends connected and a perforation in the free inner end portion of one rein disposed opposite to a lug on the corresponding 40 portion of the other rein, pressing the inner end portions of the reins together to insert the lug in the perforation, and upsetting the outer end of the lug to retain the lug within the perforation and form a permanent connection between the inner ends of the reins.

45 FREDERICK A. INGALLS.
